AIRPLANE LAUNCHING APPARATUS

Wallace E. Wilson, Wilkinsburg, Pa.

Application June 21, 1939, Serial No. 280,266

1 Claim. (CL 244—63)

My invention relates to an apparatus for facilitating the launching of airplanes, and the primary object and advantage of the invention is to provide an apparatus of the character described, which will operate in conjunction with the airplane mechanism to accelerate the take off speed of the airplane, and thereby launch the latter into the air within a relatively short distance of actual ground travel.

Further important objects and advantages of the invention are to provide an apparatus of the class stated, which will obviate the necessity of landing and take off fields of the usual enormous areas, which may be successfully employed in connection with any type or size of airplane and without involving any changes in the construction of the latter, which is simple in its construction and arrangement, durable and efficient in its use, automatically and conveniently controllable, positive in its action, and comparatively economical in its manufacture, installation, operation and maintenance.

With the foregoing and other objects in view which will appear as the description proceeds, the invention resides in the novel construction, combination and arrangement of parts herein specifically described and illustrated in the accompanying drawing, but it is to be understood, that the latter is merely illustrative of an embodiment of the invention, and that the actual needs of practice and manufacture may require certain mechanical variations from the embodiment shown. It is, therefore, not intended to limit the invention to the disclosure thereof herein illustrated, but rather to define such limitations to the scope of the claim hereunto appended.

In the drawing wherein like numerals of reference designate corresponding parts throughout the several views:

Figure 1 is a side elevational view, partly in section, of an airplane launching apparatus constructed in accordance with the invention.

Figure 2 is a transverse cross sectional view of the carriage and track structures.

Figure 3 is a side elevational view of the carriage, partly in section.

Figure 4 is an enlarged, fragmentary side elevation, partly in section, of an airplane fuselage, illustrating the releasing mechanism carried by the latter.

Figure 5 is a front view of an embodiment of a power mechanism involved in the present invention.

Figure 6 is a view on line 6—6, Figure 5.

Referring in detail to the drawing 1 denotes a straight channel of any required length, and preferably constructed of concrete. The channel is comparatively shallow and substantially rectangular in transverse cross section, and is provided with a top 2 having a narrow slot 3, which latter opens into the channel. The slot is disposed at the center of the top and extends throughout the length of the latter. The channel preferably has a sloped bottom 4 to direct any water that might enter the channel into suitable disposed drain holes 5 formed in said bottom. The top may be provided with elevated ridges 6 which are disposed along respective sides of the top opening of the slot to minimize the entrance of water or other extraneous matter into the channel. The channel is constructed in the runway of the airplane field, and the surface of the top 2 is actually a part of the surface of said field runway.

A track structure, comprising a pair of track rails 7, is suitably fixed in the channel 1. The rails extend parallel to each other, and are secured against respective side walls of said channel.

The track rails 7 are substantially V-shaped in transverse cross section, with the apexes thereof being disposed toward each other. The track rails extend throughout the length of the channel 1, and are horizontally opposed to each other.

A brake rail 8 is fixed at the center of the channel bottom 4, and extends longitudinally throughout the length of the latter. The brake rail may be insulated from the channel structure by any suitable insulation 8' for the purpose hereinafter to be described.

A carriage 9 is mounted in the channel 1, and is supported on the track rails 7. Each side of the carriage is provided with a longitudinally extending track groove 10, which latter is substantially V-shaped in transverse cross section. A ball race 11 is secured in each wall of each of said track grooves, whereby both the upper and the lower surfaces of each of the track rails is engaged by a ball race 11.

It will be evident that any other suitable type of track structure and carriage may be employed without departing from the spirit of the invention. However, it is essential that the carriage be constructed and mounted to allow same to travel freely, in either direction with a minimum of friction, both when the carriage is depressed upon the track rails by its own weight, or when said carriage is elevated against the

track rails by a pulling or lifting action exerted to said carriage in the operation of the apparatus in the manner to be described.

A brake bar 12, including a replaceable brake shoe 13, is mounted in the bottom of the carriage 9 and extends longitudinally in the latter. The brake shoe is of considerable length and width, and together with the brake bar, is projectible in the carriage to dispose said brake shoe below the plane of the lower face of the carriage bottom to frictionally engage the top of the brake rail 8 when it is desired to retard the travel of the carriage during the operation of the apparatus.

A connecting rod 14 extends through an opening 15 in the top of the carriage 9, and has its lower end secured in the brake bar 12. The connecting rod inclines rearwardly at an angle from the vertical, and the upper end thereof projects through the slot 3 at the top of the channel 1, and carries a connecting eye 16 having a swivelled attachment therewith.

A spiral spring 17 is mounted in the carriage 9 on the connecting rod 14. One end of the spring abuts against the top of the carriage, and the other end thereof abuts against the brake shoe 13, as clearly illustrated in Figure 2. The spring normally functions to force the brake shoe 13 against the brake rail 8 to effect the braking operation, while a pull on the connecting rod will elevate the brake bar and brake shoe, against the action of the spring, to clear said brake rail.

The airplane 18 to be launched is positioned at one end of the channelled runway, directly over the channel 1 and in alignment with the latter. The airplane is provided with an attaching mechanism 19, which includes a rearwardly curved connecting arm 20 projecting and depending from the airplane body. The attaching mechanism extends into the airplane body, and is maintained in position by a suitable ratchet mechanism 21. An adjusting wheel 22 is fixed to the upper end of the attaching mechanism, whereby the position of the associated connecting arm may be varied to meet conditions found in practice. A slip ball 23, having a curved passage 24, is mounted on the curved connecting arm of the attaching mechanism, and is loosely shiftable on said connecting arm.

A hitching cable 25 has a swivelled connection with the slip ball 23 and with the swivelled eye 16 on the connecting rod 14. The hitching cable is comparatively short, so when the carriage 9 is joined with the airplane 18 by the hitching cable, the latter will extend on an effective pulling angle, as shown in Figure 1. The attaching mechanism 19 is preferably disposed slightly forward of the center of gravity of the airplane, so that the pulling action of the hitching cable will not tend to overbalance the airplane on its landing gearing.

A towing cable 26, having a swivelled connection 27 with the front end of the carriage 9, extends in the channel 1, passes over a suitably supported sheave 28, and winds on a spool or drum 29. The drum and said sheave are located and suitably housed at the end of the channel remote from the starting end of the latter.

The drum 29 is operated by any suitable type of power device, preferably by an electric motor 30, which is joined with said drum by a suitable coupling clutch 31. The latter may be of the known roller type, as shown in Figure 6, which operates automatically to rotate the drum in the pulling or towing direction only, and which is

automatically operable for release to allow the free rotation of said drum in the reverse direction.

As hereinbefore stated, the brake rail or any required portion of the latter may be insulated from the channel structure by insulation 3'. By joining said insulated brake rail and the motor 30, with conductors 32 to a suitable, automatically controlled switch element 33, the latter will function to open the operating circuit to automatically suspend the operation of the motor whenever the brake shoe 13 is in contact with the brake rail, whereby the operation of the drum 29 and the towing pull on the towing cable are likewise discontinued. It is apparent that any other system of operating control may be successfully employed without departing from the spirit or sacrificing any advantages of the invention. Such systems may necessitate the presence of the attendant at location, or may be operable from points remote from the latter.

In launching an airplane with the use of my improved apparatus, the former is positioned at the starting end of the channelled runway, and the hitching cable 25 is connected with the airplane by placing the slip ball 23 on the curved connecting arm 20 of the attaching mechanism 19. The airplane motors are operated with sufficient speed to propel the airplane under its own power in the usual manner when taxying along the flying field for a take off. As soon as the airplane begins to travel under its own power, the motor 30 is started to operate the drum 29 and thereby wind the cable 26 on the latter to effect the towing operation.

When the hitching cable 25 is first drawn taut by its pulling action, the brake shoe 13 will disengage the brake rail 8, and the carriage 9 is free to travel on the rails 7, and the towing operation will be in effect. So long as the speed of the towing action is greater than the speed of the airplane under its own power, the towing action will accelerate the take off speed of the airplane. However, when the speed of the airplane under its own power exceeds the speed of the towing action, the hitching cable 25 will become slack, and the spring 17 will function to force the brake shoe 13 into frictional engagement with the brake rail. Such braking action will cause the control of the switch 33 to discontinue the operation of the motor 30 and suspend the towing operation, and the forward movement of the carriage will be immediately retarded and stopped within a very short distance. As the accelerated airplane passes over the retarded carriage the hitching cable 25 will automatically draw the slip ball 23 from the connection arm 20 to fully release the airplane from its connection with the launching apparatus.

The attaching mechanism 19 is adjustable, in the manner set forth, so that, in cases of emergency, the pilot within the airplane is enabled to shift the connecting arm 20 to a position to allow and cause the release of the slip ball 23 therefrom during the towing operation, even when the speed of the towing operation exceeds the speed of the airplane under its own propulsion, and power.

After each towing operation, the carriage 9 is returned to the starting end of the channel 1, by any suitable device or in any suitable manner. The return travel of the carriage draws back the towing cable 26 as it unwinds from the drum 29. Due to the construction and operation of the coupling clutch 31, as stated, the drum al-

ways may be freely rotated in the reverse direction.

It is of course evident that, instead of employing the preferred flexible hitching cable 25 and attaching mechanism 19 for joining the carriage 9 with the airplane, any other type of hitching mechanism may be successfully used that is capable of automatically releasing the airplane after the latter is travelling under its own power at a speed greater than the towing speed of the apparatus.

As the cost of the construction and operation of the launching apparatus is comparatively inexpensive, an airplane field may be provided with a desired number of independent or inter-dependent launching units. Each of the latter would embody a channel structure extending in a direction differing from any of the others, so that a runway best located for airplane launching, generally into the wind, may be selectively employed for launching the airplane.

The present invention provides a most efficient apparatus of its kind, which will effectively operate, in conjunction with the embodied propulsion mechanism of an airplane, for quickly accelerating the speed of the latter to produce the momentum necessary to cause the airplane to leave the ground within a comparatively short distance of travel, whereby the areas of airplane fields may obviously be greatly reduced, which embodies relatively few parts, and which may be conveniently, safely, and economically employed in the manner and for the purpose herein set forth.

What I claim is:

In an airplane launching apparatus of the character described, the combination of a channel provided with a top, said top having a narrow slot extending throughout the length thereof, a pair of elevated ridges disposed on said top at respective sides of said slot, a pair of parallel extending track rails carried by respective side walls of said channel, a carriage mounted in said channel and including revoluble means engaging said track rails for shiftably supporting said carriage on the latter, said channel having a sloped bottom, a brake rail fixed in said channel bottom, a brake bar mounted in the bottom of said carriage and being projectable below the latter to engage said brake rail, a connecting rod inclining rearwardly from the vertical shiftably extended through said carriage and having its lower end fixed in said bar, said rod projecting through said slot and carrying a swivelled eye at the upper end thereof, a spring mounted on said rod and normally functioning to force said bar against said brake rail, a hitching device connecting with said eye and with the airplane, and a power mechanism for actuating said carriage to accelerate the momentum of the airplane while the latter is travelling under its own power, the movement of said carriage when exerting a pull on said device disengaging said bar from said brake rail, said device embodying means for automatically effecting the release of the airplane therefrom when the speed of the latter exceeds the travelling movement of said carriage.

WALLACE E. WILSON.
